UNITED STATES PATENT OFFICE

FREDERICK WILLIAM BAILEY, OF PEMBROKE, ONTARIO, CANADA, ASSIGNOR TO THE
STEEL EQUIPMENT COMPANY, LIMITED, OF OTTAWA, ONTARIO, CANADA

BOOKSHELF

Application filed May 19, 1930. Serial No. 453,522.

This invention relates generally to improvements in shelves and more particularly to improvements in shelves for books and the like.

5 One object of the invention is to provide a strong, light and durable bookshelf that can be readily fitted in a case and which, while being detachable, will be rigid therein.

Another and essential object is to provide a 10 shelf of this description adapted for a free circulation of air and, at the same time, so constructed as to provide a flat resting surface for books and the like, whereby such articles will not become warped, bent or out 15 of shape, but will be in practically the same state of preservation when removed as when first placed on the shelf, irrespective of the length of time they may have been there.

With ventilated shelves at present in use 20 in offices, libraries and otherwise, matter, particularly books supported thereon, are liable after a time to get out of shape, due chiefly to unevenness in the top surface of such shelves. Frequently, too, this form of 25 shelf has, in time, become warped or distorted with the load on it. These are serious objections, particularly where expensive and expensively bound volumes and the like are concerned.

30 With my improved shelf, however, such objections do not exist, as, besides having all the advantages of thorough ventilation, the top or resting surface for the books is even and perfectly smooth and is thereby adapted 35 to support indefinitely, in normal condition, books and other matter carried thereon.

With the foregoing and other objects hereinafter more fully referred to, the novel 40 features of the invention comprise a bookshelf formed from a sheet of suitable metal having therein longitudinally extending spaced channels in which are a plurality of air ducts or openings. The unchanneled portions forming a smooth even-topped surface for the reception of books and the like. The metallic sheet is also bent on itself to 45 form reinforced back and front sides for the shelf.

In the accompanying drawings an example of the shelf is disclosed in which:

Fig. 1 is an enlarged perspective view of the shelf as a whole.

Fig. 2 is a transverse section.

Fig. 3 is a section on line 3—3 of Fig. 2.

Referring now more particularly to the 55 drawings in which like characters of reference indicate corresponding parts in each figure, A designates the shelf as a whole preferably, as here shown, formed from a single metallic sheet or section, in the smooth flat surface or top of which are provided the longitudinally extending countersunk channels or air passageways 10, and 11, spaced from one another and from the sides of the shelf to provide the flat even surfaced portions 12, 13, and 60 14, for the reception of books or the like and adapted to support such articles indefinitely without their becoming bent or out of shape. The air passageways 10, and 11, are formed with series of spaced elongated air ducts or 65 70 openings 15, and 16, which in combination with the channels 10, and 11, provide for a continuous and free circulation of air.

The material forming the shelf A is folded upon itself and bent as at 17, to form the reinforced front side 18, and is similarly folded on 75 itself and suitably bent as at 19, to form a continuous lip for detachable engagement with any suitable means in a casing or support (not shown).

Further detachable supporting means are provided at the ends of the shelf A by end pieces 20, and 21, which may be spot-welded or secured in any other suitable way to the shelf and which are each provided with a lug 85 22, for engagement with openings in the support or casing (not shown). These lugs may have a hole therethrough to engage with a suitable securing pin.

In addition to thus providing a ventilated 90 shelf with a smooth even supporting surface, the folding and bending of the metallic sheet provide reinforcement which materially strengthens the shelf as a whole and eliminates any tendency to warp or become distorted, even when carrying a capacity load.

In operation, the shelf is fitted into a casing, the lugs 22, at each end engaging with openings in the casing standards, while the continuous lip 19, on the rear side of the shelf 100

engages with any suitable means in the casting for detachably and rigidly supporting the shelf therein.

Various forms of the apparatus described
5 will suggest themselves to those skilled in the art; it is, therefore, not intended that the present application should be limited to any particular form of construction; modifications may be made in the apparatus above described
10 within the scope of the claims, without departing from the spirit or scope thereof.

What I claim for my invention is:

1. A shelf for books and the like, comprising a single sheet of metal having a continuous smooth surface, a plurality of spaced longitudinally extending channels formed in the surface having openings therein at spaced intervals relative to said channels, one side of the sheet being extended downwardly and
15 folded upon itself to form a reinforcing side, the opposite side of said sheet being extended downwardly and folded upon itself to form a continuous lip, end pieces rigidly secured between the sides and co-ordinating with the
20 channelled surface and formed with projections for detachable engagement with a support.
25

2. A shelf formed from a single metallic sheet having spaced channels in the top
30 formed with ventilating openings in said channels, the front of the shelf being extended and folded upon itself at right angles to the channelled top to form a reinforcing side, the rear being extended and folded upon itself
35 and bent to form a continuous supporting lip, end pieces co-operating with the channelled top and having supporting means integral therewith.

In witness whereof I hereunto set my hand.

40 FREDERICK WILLIAM BAILEY.
